UNITED STATES PATENT OFFICE.

HORACE W. NORWOOD, OF PHILADELPHIA, PENNSYLVANIA, ASSIGNOR TO THE NORWOOD SPARK PREVENTIVE AND SMOKE CONSUMING COMPANY, OF CAMDEN, NEW JERSEY.

WATER-ELEVATOR.

SPECIFICATION forming part of Letters Patent No. 272,463, dated February 20, 1883.

Application filed April 3, 1882. (No model.)

To all whom it may concern:

Be it known that I, HORACE W. NORWOOD, a citizen of the United States, and a resident of the city and county of Philadelphia, in the 5 State of Pennsylvania, have invented certain new and useful Improvements in Water-Elevators, of which the following is a specification, reference being had to the accompanying drawings, wherein—

10 Figure 1 is an elevation, partly in section, showing the application of my invention for elevating or excavating the bed of a river. Fig. 2 is a longitudinal vertical section of the jet appliance. Fig. 3 is a transverse section of the 15 same, and Fig. 4 is a detail broken plan.

My invention has relation to elevators for raising water, sand, mud, grain, and other similar materials by means of the propelling force 20 of a jet of steam, compressed air, or liquid under pressure; and it consists in the novel construction of the jet appliance or elevator, as hereinafter specifically described and claimed.

Referring to the accompanying drawings, I will first describe the construction and operation 25 of the jet appliance, in order that its application to a pipe for elevating and conveying purposes may be more readily understood.

Referring to Fig. 2 thereof, A represents a shell or body, of globular or other desired form, 30 provided with a discharge-opening, a, the interior of which is formed with a conical or tapered recess, a'. Said shell has a chamber, B, provided with radial lugs b b, upon which seats a pipe, C, the bore of which is of the same diameter as that of the opening a. Said pipe is formed with a tapered end, c, which enters recess a', and is provided with an eccentric or 35 crank, d, fitted in or resting between the edges or sides of a slot, c'. Said eccentric is secured to a shaft, D, which has bearings in shell A, as shown at d' d'', and is provided with an operating-handle, d''. By moving the latter the eccentric or crank d is oscillated, and its lower end working in slot c' causes the tube C to reciprocate to move its end c to and from the 40 walls of tapered recess a', to adjust the extent of space between said parts to regulate the amount of steam, compressed air, or liquid under pressure designed to pass therethrough,

and thereby vary the dimensions or area of 50 such jet formed thereby.

E indicates an opening in the side of the shell A, communicating with chamber B, and is designed to receive a pipe leading from a steam-boiler, air-compressor, or other source 55 of jet-supply. Such construction affords a device having a free and unobstructed opening or bore from end to end, of the same diameter throughout, a steam or &c. chamber surrounding the walls of the central bore for a 60 part of its length. Said steam or other jet-forming medium is admitted to said bore in the form of an annular jet, and the thickness or extent of the same may be varied, as desired. The radial lugs b b support the pipe C 65 on all sides from end to end without materially diminishing the extent of the steam-chamber B, and prevent the pressure of such steam acting upon the end c of pipe C to move the same laterally to cause an irregular opening 70 between said end c and tapered recess a'. Such irregularity of said opening, if allowed to occur, would result in the formation of an annular jet of greater power on one side than on the other, thereby reducing the effective 75 working-power of said jet; but by employing the lugs b b the end c of pipe C is rigidly held in position to maintain its due relation with tapered recess a' to form an annular jet-space between said parts, of equal area throughout. 80 Such appliance is used for raising or conveying sand, mud, or other similar solid, fluid, or semi-fluid material by securing several or any number of them to a pipe or conduit, F, as shown in Fig. 1, wherein G represents the 85 bed of a river designed to be raised or excavated. Said pipe F is formed in sections f, f', f'', &c., each such section being screwed to a nipple, a'', flange-bolted to the ends of the jet appliances, as shown at a''. The end f''' of pipe 90 F is of such length that it will enter said river-bed, as shown at f'', so that the pipe F will be filled with water to the line of the surface of the river, as indicated. The first jet appliance is located on said pipe a short distance above 95 the surface of such water, as shown, and the remaining jet appliances may be placed thereon at any desired distance apart, such distance

depending upon the pressure designed to be carried in the steam-boiler or other source of jet-supply.

K represents a steam-pipe, connected by branches $k\ k'$ to the jet appliances, as shown, and is provided with a valve, K'. Said pipe K may lead from a boiler upon a scow, L, as illustrated; or said boiler may be in any other suitable location. The sliding tube C in each jet appliance being duly adjusted to admit the required thickness or extent of annular jet through each appliance to pipe F, the valve K' is opened, whereupon steam passes from pipe K into chamber B of each appliance, and thence through annular tapering opening c^2 , to the interior of pipe F in the form of an annular jet, which travels near to or along the inner walls of pipe F, so that along the length of the latter at stated intervals a steam-jet is playing or entering therein, the result whereof is as follows: The jet A', or that one nearest the surface of the water, first creates or produces a suction or vacuum in the space F' in pipe F, or in that part of said pipe included between the jet A' and the top of the water in pipe F, which corresponds to the level or surface of the river. Said water in said pipe thereupon rises therein until it enters the area or path of annular jet in A', and is at once carried forward with great velocity by said jet, until the force of the latter is about to expend itself; but before such result occurs said water has been carried to and projected into the area of the next or second jet in appliance A², and is propelled forward thereby, as described, and discharged from pipe F onto a chute, or otherwise, as desired. As soon as such water in pipe F rises therein and is conveyed therethrough the river-bottom material G is forced into said pipe by the pressure of water above it, and rises therein until it meets the jets of steam, when it is propelled thereby through and out of said pipe, as above described. After being discharged therefrom the material may be conducted to an amalgamator for recovering any contained precious metal; or, if such river-bottom material contain no ore, it may be deposited upon low lands or otherwise disposed of after passing out of pipe F.

In this manner my invention may be used for aiding in extracting ore from river-bottoms, dredging the same, raising water from wells or rivers, loading and unloading grain, or for other similar purposes.

When it is used for loading and unloading grain, compressed air is substituted for steam, and it becomes desirable to regulate the discharge of the grain from the pipe F, so that said grain will not be propelled out thereof with such force as to comminute the same. Hence the sliding tube C in the jet appliance adjacent to the discharge-opening in said pipe F is ad-

justed to admit a jet of very small power into pipe F. Consequently, when the grain reaches said jet, the latter propels the same forward or upward with force just sufficient to cause the grain to pass out the discharge-opening in pipe F to fall to or be conveyed to a receiver without being broken into fragments.

It will be noticed that the material, after being drawn up in pipe F by suction induced by the first jet appliance, enters the area of said jet, or becomes confluent therewith, and is thereby forced, propelled, or carried forward or upward to next jet in pipe F, which in turn passes such material to the next jet above or beyond it, and so on throughout the entire length of the conveying tube or conduit, each successive jet giving a fresh or new impulse to such material. Hence it may be conveyed to any desired distance or raised to any suitable height by merely increasing the number of jet appliances and extending the length of the conveyor tube or conduit.

The end of pipe F always enters the material to be raised or conveyed, so that it will rise to its level in said pipe, thereby diminishing the extent of vacuum to be produced therein to cause such material to rise to the first jet appliance. Such material being once set in motion to rise to said jet, said movement is maintained until all the material designed to be raised has passed into and been propelled through pipe F.

I have described steam and compressed air as the media for producing the jets; but I do not limit myself thereto, as water or other liquid under pressure may be used, as well as any other suitable material.

What I claim as my invention is—

1. A water-elevator composed of a shell or casing having aligning induction and eduction openings of an equal bore throughout, a chamber, B, provided with radial lugs $b\ b$, upon which rest the tube C, having tapered end c , entering a correspondingly-formed recess in the induction-outlet, and a steam or side opening leading into said chamber, substantially as shown and described.

2. The combination, in a water-elevator, of the casing or shell A, having induction and eduction openings of equal bore throughout, tapered recess a' , steam or side opening, E, chamber B, radial lugs $b\ b$, the pipe C, with tapered end c , and mechanism for adjusting or moving said pipe C, substantially as shown and described.

In testimony that I claim the foregoing I have hereunto set my hand this 15th day of February, A. D. 1882.

HORACE W. NORWOOD.
